UNITED STATES PATENT OFFICE.

WILLIAM EVERETT VER PLANCK, OF ERIE, PENNSYLVANIA, ASSIGNOR TO GENERAL ELECTRIC COMPANY, A CORPORATION OF NEW YORK.

CONTROLLING MECHANISM FOR HIGH-COMPRESSION INTERNAL-COMBUSTION ENGINES.

1,170,200.

Specification of Letters Patent.

Patented Feb. 1, 1916.

Application filed July 29, 1914. Serial No. 853,866.

To all whom it may concern:

Be it known that I, WILLIAM EVERETT VER PLANCK, a citizen of the United States, residing at Erie, county of Erie, State of Pennsylvania, have invented certain new and useful Improvements in Controlling Mechanism for High-Compression Internal-Combustion Engines, of which the following is a specification.

10 This invention relates to mechanism for regulating the feed of liquid fuel to the working cylinders of internal combustion engines of the high compression type, and its object is to simplify and rearrange the 15 parts and make the organism more efficient.

The system of regulation to which my invention relates may be briefly stated to be one in which the liquid fuel is fed to the engine by pumps, one for each cylinder; the 20 quantity of fuel depending upon the effective stroke of the pumps. A pressure-responsive device is interpolated in the stream of lubricating oil which is constantly fed to the engine bearings by a force pump. The 25 flow of oil can be throttled by a valve controlled by the speed governor of the engine, but any checking of the flow by said valve causes the pressure-responsive device to move in order to relieve the throttling action. This movement of said device is 30 utilized to vary the effective stroke of the fuel pumps, so that their delivery corresponds directly with the action of the speed governor.

35 The novel features of my invention will appear from the following detailed description taken in connection with the accompanying drawings, in which—

Figure 1 is an end elevation of an engine 40 embodying my improvements; Fig. 2 is a side elevation of the same, partly in section; Fig. 3 is a top plan view of Fig. 2; Fig. 4 is a sectional elevation of a fuel pump; Fig. 5 is a vertical section, on a larger scale, of the air pump and the regulating mechanism of the engine; Fig. 6 is a sectional view of the sleeve valve, on a larger scale, and Fig. 7 is a sectional view of the lubricating feed pump, in a different position from that 50 shown in Fig. 5.

The main shaft 1 of the engine is equipped with eccentrics 2, each of which drives a fuel pump 3, one for each of the working cylinders 4, of which there may be

any number. The pumps are preferably of that type in which a plunger makes a stroke of constant length, but the region in which it operates can be varied to vary the delivery of the pump. In the drawings, the pump plunger 5 is actuated by a bent lever 6, pivoted to the eccentric rod 7 and fulcrumed by a strap 8 on an eccentric 9 mounted on a shaft 10. By turning this shaft, the actual fulcrum of the lever, which, is at the center of the circular eccentric, will be raised or lowered, and the region in which the pump plunger operates will be correspondingly changed. The means by which the shaft 10 is oscillated in accordance with the speed variations of the engine will now 70 be described.

At some point on the shaft 10 is an arm 11 engaging with a pressure responsive device. This is preferably a plunger 12, tubular throughout almost its whole length and 75 working in a cylinder 13. The end of the arm 11 preferably rests on a collar 14 on the plunger, while above the arm is a washer 15 loose on the plunger and urged downwardly by a helical spring 16, preferably encircling a guide 17 for the upper end of the plunger. Above the guide is a chamber into which the upper portion of the tubular plunger projects. The top of the plunger is closed, but it has small ports 18 in its walls 85 which are controlled by a sleeve valve 19 having similar ports 20. A spring 21 urges this valve upward so that its ports will not register with those in the plunger. The valve is controlled by the lever arm 22 of the 90 speed governor 23, which rests upon the upper end of the stem 24 of the valve, said stem being guided in a long bearing 25.

Means are provided for forcing fluid continuously into the lower end of the cylinder 95 13, up through the tubular plunger and out through the ports 18 and 20. The rate of flow is determined by the position of the sleeve valve and whether its ports register fully or only partially with those in the 100 plunger. Any retardation of the flow by the raising of the valve causes a building up of the pressure in the cylinder 13, which tends to lift the plunger against the tension of the spring 16, until its ports come in line 105 once more with those in the sleeve valve. This movement of the plunger is imparted to the arm 11 and thus causes an oscillation of

the shaft 10 and a variation in the delivery of the fuel pumps. The parts are so arranged that a drop in the speed of the engine causes the governor arm 22 to rise, which 5 results in an upward movement of the tubular plunger and a lowering of the fulcrum of the lever 6, thereby shifting the region of operation of the fuel pump in such wise that it will deliver an increased quantity of fuel, 10 and thereby the power of the engine will be increased and its speed restored to normal.

For the purpose of producing the constant flow of fluid through the pressure-responsive device, I prefer to utilize the lubricating 15 system of the engine. This has a pump whose plunger 26 is preferably attached to the strap of the eccentric 27, mounted on the shaft 1 and having opposite to the pump plunger an arm 28 which operates the air inlet valve 29 of the scavenging air pump 30. The plunger 26 works in a cylinder 31 which is mounted on a rocking joint 32 to avoid the necessity of any joints between the eccentric and the plunger. The rocking motion of the 25 cylinder also serves to open and close the suction port 33 and the delivery port 34 of the oil feed pump. The lubricant is sucked through a strainer 35 in a reservoir 36 in the base of the engine frame, and delivered 30 through a pipe 37 to the bottom of the cylinder 13. A ball check valve 38 prevents any return of the oil when the engine stops and prevents pulsations due to intermittent reaction of fuel pumps. An air chamber 39 35 keeps a steady pressure on the oil flowing to the cylinder 13. From the tubular plunger 12 the oil enters the chamber surrounding its upper portion and thence flows out by the pipe 40 to a downspout 41 delivering the oil 40 to a header 42 in the base of the engine from which it is distributed by branches 43 to the bearings of the engine. A relief valve 44 is located at the junction of the pipes 40 and 41, which has a hand wheel 45 for adjusting 45 it by hand, the overflow returning to the reservoir by the pipe 46. A bypass, controlled by the stop valve 47, enables the engineer to cut out the pressure responsive device without interrupting the lubrication 50 of the engine, by shunting the oil from the delivery pipe 37 directly into the downspout 41.

The operation may be briefly recapitulated as follows: The lubricating oil pump 26 55 delivers a constant supply of oil to the cylinder 13, from which it flows through the tubular plunger 12 to the bearings of the engine. The speed governor, by means of the sleeve valve 19, checks the flow of oil 60 when the load on the engine increases and thus causes a pressure to build up in the cylinder 13 which moves the plunger 12 against the tension of the spring 16 and thus, through the arm 11, shifts the fulcrum of the 65 lever 6 actuating the fuel pump plunger and

so causes said pump to supply more fuel. Upon a rise in speed, the governor brings about an opposite movement of parts to cut down the fuel supply. If the circulation of lubricating oil should be checked owing to a 70 leak in the system or the failure of the pump, the engine would automatically shut down and thus prevent burning out of the bearings.

In accordance with the provisions of the patent statutes, I have described the principle of operation of my invention, together with the apparatus which I now consider to represent the best embodiment thereof; but I desire to have it understood that the apparatus shown is only illustrative, and that the 75 invention can be carried out by other means.

What I claim as new and desire to secure by Letters Patent of the United States, is:—

1. The combination with a high compression internal combustion engine, of fuel pumps for feeding fuel to the cylinders thereof, adjustable fulcrsa for said pumps, a pressure - responsive device for shifting said fulcrsa, a lubricating system for the engine forcing oil through said pressure-responsive device, and a speed governor controlling the flow of oil through said device. 85

2. The combination with a high compression internal combustion engine, of fuel pumps for feeding fuel to the cylinders thereof, adjustable fulcrsa for said pumps, a pressure - responsive device for shifting said fulcrsa, a lubricating system for the engine forcing oil through said pressure-responsive device, a speed governor controlling the flow of oil through said device, and means for by-passing the oil around said pressure-responsive device. 95

3. The combination with a high compression internal combustion engine, of fuel pumps for feeding fuel to the cylinders thereof, a rock-shaft, eccentrics thereon, levers mounted on said eccentrics and adapted to drive said pumps, a pressure-responsive device operatively connected with said rock-shaft, means for forcing fluid through said pressure-responsive device, and a speed governor controlling the flow of such fluid. 105

4. The combination with a high compression internal combustion engine, of a pump for supplying fuel thereto, and a regulating means for the pump, said regulating means embodying a pressure - responsive device comprising a cylinder, a tubular plunger therein, closed at its upper end and containing ports at that end, a ported sleeve valve working on the upper portion of said plunger, means for forcing fluid up through said plunger, a helical spring opposing the pressure of said fluid, and a speed governor 110 controlling said sleeve valve. 120

5. The combination with an internal combustion engine, of a fuel pump therefor which is regulated by fluid pressure, a lubricating system for the engine, and a single 130

5 pump for supplying fluid for regulating the
fuel pump and lubricant to the lubricating
system.

6. The combination with an internal com-
bustion engine, of a fuel pump therefor hav-
ing a mechanism adapted to be operated by
fluid pressure to regulate the pump, a lubri-
cating system for the engine connected in
series with said mechanism, and a pump for
10 forcing lubricant through said mechanism
and system.

7. The combination with an internal com-
bustion engine, of a fuel pump therefor hav-
ing a mechanism adapted to be operated by
15 having fluid under pressure forced through
it to regulate the pump, a pump for forcing
fluid through said mechanism, and a lubri-
cating system for the engine connected in

series with and on the discharge side of said
mechanism whereby the fluid forced through 20
the mechanism is utilized to lubricate the
engine.

8. The combination with an internal com-
bustion engine, of a fuel pump therefor hav-
ing a mechanism adapted to be operated by 25
fluid pressure to regulate the pump, a lubri-
cating system for the engine connected in
series with said mechanism, and a pump
operated from the engine for forcing lubri-
cant through said mechanism and system. 30

In witness whereof, I have hereunto set
my hand this 27th day of July, 1914.

WILLIAM EVERETT VER PLANCK.
